UNITED STATES PATENT OFFICE.

HENRY G. LYKKEN, OF GRAND FORKS, NORTH DAKOTA.

PNEUMATIC GRAIN-ELEVATOR.

1,123,335.

Specification of Letters Patent.

Patented Jan. 5, 1915.

Application filed September 6, 1913. Serial No. 788,491.

To all whom it may concern:

Be it known that I, HENRY G. LYKKEN, a citizen of the United States, residing at Grand Forks, in the county of Grand Forks and State of North Dakota, have invented a new and useful Pneumatic Grain-Elevator, of which the following is a specification.

This invention has reference to improvements in pneumatic elevators designed for use in connection with seeds, grain or other comparatively dry, granular or more or less finely divided substances of which grain may be taken as typical, wherefore the term grain will be used in the following description, with the understanding that its meaning is comprehensive enough to cover any substance for which the machine of the present invention is adapted.

It is the object of the present invention to provide a machine of a type which in compactness is especially adapted for portability, and which may be readily employed for elevating grain to a desired height.

In accordance with the present invention there is provided an air suction and forcing means, and on the suction side there is provided a suction duct or pipe which at an appropriate point enters an expansion chamber from which it is branched to the suction side of the air suction and forcing means, and also to the pressure side thereof. Within the expansion chamber there is provided means for permitting the flow of air to the suction side of the pneumatic suction means without carrying the grain with it, and the latter is then allowed to gravitate toward the pressure side of the pneumatic suction means, and the arrangement is such that there is provided a column of grain which will gravitate into the outflowing stream of air and hence be carried to the desired high point, and at the same time will operate as an automatic check preventing the flow of air under pressure toward the suction side of the suction means back through the expansion chamber.

One important feature of the present invention, and which aids materially in the simplification of the structure, is the arrangement whereby there is provided between the expansion chamber and the discharge side of the suction means or blower a column of grain or other material when the device is in operation, of such a weight as to

there counterbalance the effect of the suction side of the blower.

The invention will be best understood from a consideration of the following detailed description, taken in connection with the accompanying drawings forming a part of this specification, with the further understanding that while the drawings show a practical form of the invention, the latter is not confined to any strict conformity with the showing of the drawings, but may be changed and modified so long as such changes and modifications mark no material departure from the salient features of the invention.

In the drawings:—Figure 1 is a side elevation with parts in section of a grain elevator embodying the present invention. Fig. 2 is an end elevation viewed from the right hand side of Fig. 1. Fig. 3 is a section on the line 3—3 of Fig. 2. Fig. 4 is a section on the line 4—4 of Fig. 3. Fig. 5 is a side elevation with parts in section of a somewhat different embodiment of the invention from that of the preceding figures. Fig. 6 is a section on the line 6—6 of Fig. 5 and showing some parts broken away to reveal more distant parts.

The apparatus of the present invention may be either stationary or portable, but is particularly adapted for portability.

The supporting frame of the device as shown in Figs. 1 to 4 may comprise beams or sills 1 with cross pieces 2 and uprights 3 in turn carrying other beams 4 on which are mounted journal boxes 5 for a shaft 6 at one end of which latter there may be provided a pulley 7, which may be taken as indicative of any means for the application of power to the shaft 6.

Mounted in the framework is a casing 8, and the shaft carries blades 9 within the casing, which blades and casing may follow the usual practice employed in suction and force blowers.

At a high point on the casing 8 there is provided another casing 10 inclosing a chamber 11, which because of its function may be termed an expansion chamber and one end of this chamber is entered by a duct 12 said duct communicating with the chamber preferably at a low point thereof but above the casing 8.

Within the chamber 11 there is arranged a series of baffles 13 which may be simply

transverse plates arranged upright in the chamber and terminating short of both the top and bottom of the chamber. Above the baffles 11 the chamber has side extensions 14 from which drop ducts 15 to the intake throat 16 of the blower. These ducts 15 are on opposite sides of the casing 8 and open through the said opposite sides into the interior of the casing.

- 10 The outlet of the casing is by way of a duct 17 which may be generally tangential to the casing as is customary, but in the particular arrangement of the drawings, and especially in the structure shown in Figs. 1, 2, 3 and 4 this duct 16 is in rising relation to the casing, and is assumed to lead to the high point to which it is desired to elevate the grain.

Leading from a low point of the expansion chamber 11 on the side thereof opposite the duct 12 is another duct 18 and both ducts are located below the baffles 13 so that the latter are out of the direct path of the grain passing through the expansion chamber from the duct 12 to the duct 18. In the drawings the duct 18 is shown as conforming to the curvature of the casing 8 and is arranged exterior thereto on the corresponding end, and this duct has an outlet throat 19 entering the tangential outlet duct 17 of the blower.

Within the duct 18 there is a valve 20 so arranged that it will close toward the chamber 11 should there be even a moderate flow of air through the duct 18 from the throat 19 toward the chamber 11, but this valve will open readily to even a slight weight.

If it be assumed that the duct 12 is carried into a body of grain to be elevated, and that the rotary member 9 of the blower is set in motion in a manner to create a current of air through the duct 12 toward the chamber 11, then such current of air will carry grain with it. As soon as the current of air with the grain reaches the expansion chamber 11 the speed of this current of air is materially reduced, so that it is no longer able to hold the grain in suspension, or to propel it, whereupon the grain gravitates on to the downwardly curved floor of the duct 8 which conforms in shape to the corresponding end of the casing 8, while the air without the grain rises through the baffles 13 into the chamber extensions 14, and from thence finds its way through the ducts 15 into the intake throat of the blower casing, and this air free from grain is driven through the outgoing duct 17.

Practice has demonstrated that the baffles 13 are effective in slowing up the air stream entering the chamber 11 and in preventing the grain from following the air stream into the ducts 15, while the grain thus escaping from the air stream falls upon the downwardly curved floor of the duct 18 and gravi-

tates toward the throat 19, the valve 20 being in the meantime closed by the superior pressure of air on the outgoing side of the blower. The grain soon accumulates in the duct 18 and rises until it is able by its weight to overcome the valve 20 and the air pressure against the same, whereupon the grain falls to and through the throat 19 and into the outgoing stream of air passing through the duct 17. This stream of air is a strong stream and consequently the grain is carried along with it to the desired high point, while grain accumulates in the duct 18 until it forms a mobile and yet effective seal against circulation of air from the outgoing side of the blower toward the chamber 11, but this does not interfere with the dropping of the grain by gravity through the duct 18 and past the throat 19 and from thence into the outgoing stream passing along the duct 17. The valve 20 is effective only at the beginning of the operation, and thereafter the valve is inactive, its place being taken by the column of grain accumulating within the duct 18.

It will be observed that the only movable part of the whole structure is the rotor within the casing 8.

In Figs. 5 and 6 there is shown a somewhat different embodiment of the invention from that illustrated in Figs. 1 to 4. In the modified form there is shown a casing 8^a through which there extends a shaft 6^a carrying a multiple series of fan or blower blades 9^a and the casing is divided by partitions 21 into a corresponding number of compartments with stationary blades 22 on the partitions coacting with the radial blades or rotors 9^a.

The multi-blower of Figs. 5 and 6 has an intake duct 15^a communicating with one end of the multi-blower, and at the other end with the multi-blower discharges into a discharge pipe or duct 17^a.

The intake 15^a is in communication with a chamber 11^a within a corresponding casing 10^a into which discharges an intake duct 12^a. The chamber 11^a is in the nature of an expansion chamber, and from it leads another duct 18^a in turn leading into a chamber 23 within a casing 24.

Within the chamber 11^a between the ducts 12^a and 18^a on one hand, and 15^a on the other hand, is a screen 25.

The chamber 23 communicates with the discharge duct 17^a through a throat 19^a in communication with the chamber 23.

The shaft 6^a is supported in bearings 5^a in turn upheld by beams 4^a which may form part of the supporting framework of the structure shown in Figs. 5 and 6.

The height of the chamber 11^a above the chamber 23 is sufficient to provide a column of grain in the duct 18^a and chamber 23 to act as an automatic check or valve prevent-

ing flow of air from the outgoing or discharge duct 17^a and the chamber 11^a, the arrangement being such that the grain in the duct 18^a and chamber 23 will find its way into the discharge duct 17^a to be carried by the air stream flowing therethrough to the desired high point of discharge.

The operation of the structure shown in Figs. 5 and 6 is in general the same as that shown in Figs. 3 and 4. Because of the suction created in the duct 15^a and chamber 11^a the air stream is created in the duct 12^a and the latter coming from a supply of grain causes the grain to be drawn into the chamber 11^a where the expansion of the air permits the grain to fall into the duct 18^a, while the air itself passes through the screen 25 into the duct 15^a and so to the blower, being discharged through the duct 17^a. The grain gravitates through the duct 18^a into the chamber 23 and from thence passes out through the throat 19^a into the discharge stream of air from the blower and is carried thereby to the desired high point, while the column of grain within the duct 18^a is of sufficient height to prevent any circulation of air through the duct 18^a from the pressure side of the blower toward the suction side thereof.

30 The structure shown in Figs. 5 and 6 is disclosed in my application No. 703,044, filed June 11, 1912, and to this extent the present application is a continuation of the said prior application.

35 What is claimed is:—

1. A pneumatic elevator comprising a fan or blower, a discharge pipe leading therefrom to a point of disposal of the material being elevated, a suction pipe designed to receive the material to be elevated, and connected with the intake side of the fan or blower, said pipe including an expansion chamber, and a pipe extending between the expansion chamber and the outlet or discharge pipe of the fan or blower and of a height to provide a column of material therewithin of a weight to nullify the difference of air pressure between the outlet of the fan or blower and the expansion chamber.

2. In a pneumatic elevator, a fan or blower, and a feeding duct leading to both the intake and discharge ends of the fan or blower, the portion of the duct connected to the discharge end of the blower extending to such a height above said connection as to provide for a column of material in the duct of a weight to counterbalance the effect of the suction at the intake end of the fan or blower.

3. A pneumatic elevator comprising a fan or blower having a discharge pipe leading in an upward direction to the desired high point of disposal, an intake pipe adapted to lead to the material to be elevated and

provided with a downwardly extending portion leading into the uprising discharge pipe and including an expansion chamber at the high point of the downwardly leading duct, and a duct leading from a high point of the 70 expansion chamber to the intake of the fan or blower, the duct leading into the discharge pipe from the intake pipe being of a height to provide a column of grain of a weight to operate as an automatic check 75 counterbalancing the difference between the pressure and suction sides of the blower.

4. In a pneumatic elevator, a fan or blower, a feeding duct leading to the intake and discharge ends of the fan or blower with the portion of the duct connected to the discharge end of the blower extending to such a height above such connection as to provide for a column of material in the duct of a weight to there counterbalance the effect of the suction at the intake end of the fan or blower, and a valve in and near the lower end of the duct leading to the discharge end of the fan or blower, said valve being responsive to be closed by return air 90 streams in said duct.

5. A pneumatic elevator comprising a fan or blower, a casing thereon inclosing an expansion chamber, baffles within the expansion chamber stopping short of both the top and bottom thereof, a duct leading from the upper portion of the expansion chamber to the intake of the fan or blower, an inlet duct opening into the space in the expansion chamber below the baffles, and another 100 duct leading from the space in the expansion chamber below the baffles at a point remote from the intake duct and extending in a downward direction to and communicating with the outlet or pressure side of the 105 fan or blower.

6. A pneumatic elevator comprising a fan or blower, a casing thereon inclosing an expansion chamber, baffles within the expansion chamber stopping short of both the top and bottom thereof, a duct leading from the upper portion of the expansion chamber to the intake of the fan or blower, an inlet duct communicating with the expansion chamber at a low point and opening into the space 110 therein below the baffles, and another duct leading from the space in the expansion chamber below the baffles at a point remote from the intake duct and extending in a downward direction to and communicating with the outlet or pressure side of the fan or blower, said last named duct being provided with a valve for closing it against flow of air from the outlet side of the blower toward the intake side thereof.

7. A pneumatic elevator comprising a fan or blower, a casing above the fan or blower and having a series of transverse baffles therein stopping short of the top and bottom of said casing, air ducts connecting the 130

- 5 top portion of the casing with the intake of the fan or blower, an inlet duct leading into the casing at a low point thereof and communicating directly with the space below the baffles, and another duct leading from a like low point of the casing to that at which the inlet duct enters and in a downward direction and opening into the discharge side of the blower.
- 10 8. A pneumatic elevator comprising a fan or blower, a casing above the fan or blower and having a series of transverse baffles therein stopping short of the top and bottom of said casing, air ducts connecting the 15 top portion of the casing with the intake of the fan or blower, an inlet duct leading into the casing at a low point thereof communicating directly with the space therein below the baffles, and another duct 20 leading from a like low point of the casing to that at which the inlet duct enters in a downward direction and opening into the discharge side of the blower, the last-named duct having a contracted throat where opening 25 into the discharge side of the blower.
9. A pneumatic elevator comprising a fan or blower, a casing above the fan or blower and having a series of transverse baffles therein stopping short of the top and bottom 30 of said casing, air ducts connecting the top portion of the casing with the intake of the fan or blower, an inlet duct leading into the casing at a low point thereof and communicating directly with the 35 space therein below the baffles, another duct leading from a like low point of the casing to that at which the inlet duct enters in a downward direction and opening into the discharge side of the blower, the last-named 40 duct having a contracted throat where opening into the discharge side of the blower, and a valve in the last-named duct adjacent to the contracted throat and responsive to close against the passage of air streams in a 45 direction toward the casing on top of the blower.
10. A pneumatic elevator provided with a fan or blower having a duct extending between the suction and pressure sides of the 50 fan or blower and including means for the separation of material from air streams passing to the fan or blower, said duct being of a height on the pressure side of the fan or blower to provide a column of material being elevated of a weight to counteract the difference in pressure between the suction and pressure sides of the fan or blower.
11. A pneumatic elevator comprising a 55 fan or blower, a casing thereon inclosing an expansion chamber, a duct leading from the

upper portion of the expansion chamber to the intake of the fan or blower, an inlet duct communicating with the expansion chamber at a low point thereof and another 65 duct leading from a low part of the expansion chamber at a point remote from the intake duct and extending in a downward direction to and communicating with the outlet or pressure side of the fan or blower, 70 said last-named duct being provided with a valve for closing it against flow of air from the outlet side of the blower toward the intake side thereof.

12. A pneumatic elevator comprising a 75 fan or blower, a casing above the fan or blower, air duct connections from the top portion of the casing to the intake of the fan or blower, a duct leading into the casing at a low point thereon and another 80 duct leading from a low point of the casing in a downward direction and opening into the discharge side of the blower, the last-named duct having a contracted throat where opening 85 into the discharge side of the blower.

13. A pneumatic elevator comprising a fan or blower, a casing above the fan or blower, means for directing air from a high point of the casing to the intake of the fan or blower, means for leading air and material to be elevated into the casing at a low point therein, a duct leading from the casing at a low point thereof distant from the inlet to the casing and opening into 95 the discharge side of the blower, said duct having a valve therein adjacent to its point of communication with the outlet side of the fan or blower and responsive to close against the passage of air streams from the blower 100 toward the casing on top of the latter.

14. A pneumatic elevator comprising a fan or blower, a casing above the fan or blower, air duct connections from the top portion of the casing to the intake side of the fan or blower, a duct leading into the casing at a low point thereof, another duct leading from a low point of the casing in a downward direction and opening into the discharge side of the blower and there having a contracted throat, and a valve in the last-named duct adjacent to the contracted throat and responsive to close against the passage of air streams in a direction toward the casing on top of the blower.

In testimony, that I claim the foregoing as my own, I have hereto affixed my signature in the presence of two witnesses.

HENRY G. LYKKEN.
